UNITED STATES PATENT OFFICE.

LOUIS EDOUARD ANTOINE DUFLOL, OF ST. PETERSBURG, RUSSIA.

APPARATUS FOR RAISING AND LOWERING LOADS.

No. 887,608.

Specification of Letters Patent.

Patented May 12, 1908.

Application filed March 17, 1906. Serial No. 306,624.

To all whom it may concern:

Be it known that I, LOUIS EDOUARD ANTOINE DUFLOL, a citizen of Switzerland, and a resident of St. Petersburg, Russia, have invented certain new and useful Improvements in Apparatus for Raising and Lowering Loads; of which the following is a specification.

This invention relates to apparatus for raising and lowering loads by the direct action of compressed air and is especially applicable for delivering ammunition on board war-ships.

The invention consists in placing the load to be raised at the bottom of an elevator tube or conduit on a piston whose circumference fits closely the walls of the tube.

Compressed air is introduced under the piston which is raised with the load to the desired height. Automatic stoppage is determined by the quantity of air and by an orifice for neutralizing the pressure in the tube.

The load to be lowered is placed on the piston at the top of the tube in which it descends freely. The rapidity of the descent is regulated by an air outlet orifice at the foot of the tube.

The invention is hereinafter particularly described with reference to the accompanying drawing in which,

Figure 1 is a part vertical section and a part side elevation of the preferred construction of apparatus. Fig. 1^a is a detail, and Fig. 2 is a vertical section and plan showing a modified arrangement of the loading station.

The elevator is composed of an air tight tube or conduit B. This tube may be in a single piece or formed of several parts connected by air tight joints. Its position may be vertical or inclined or it may permit of change of direction by means of suitable connections.

In practice, for the rapidity of service, the loading station D preferably comprises two cylinders a, a' of the same section as the elevator tube B arranged in the form of a V. When one of these cylinders is in operative position directly beneath the tube B the other cylinder is in position to receive a piston C supporting a load designated in the drawing as A.

The cylinders a or a' are free to oscillate around a pivot d. At the bases of these cylinders are arranged passages c and c'; the pivot d has two orifices, one d' which is longi-

tudinal and receives the compressed air from a reservoir G while the other orifice e is radial and is disposed in the prolongation of the axis of the tube B and offers a passage to the compressed air at the moment when one of the passages c, c' of the cylinders a, a' is co-axial with the tube B.

A suitable coupling is provided to prevent leakage of compressed air from between the cylinders a or a' and the tube B. The ends of said tube and cylinders have flanges g, h, respectively, beveled in the same direction so that when either cylinder is moved under the tube the two bevels form a conical seat.

A sleeve f on the tube has a conical end f' which, when the sleeve is lowered, rests on the two bevels and forms an air-tight joint.

As shown in Fig. 1, the raising and lowering of the sleeve is accomplished by screw threads on the tube and sleeve and the latter is provided with a hand wheel f² by means of which it is rotated: In the modification shown in Fig. 2, the sleeve is adapted to slide on the tube and is raised and lowered by means of a lever i' pivoted on a fixed bracket i² and connected to the sleeve by a rod i³. When the sleeve f is lowered into the flanges it opens a normally seated spring controlled valve I in a controlling conduit x which is connected with the compressed air reservoir G, said valve being connected with the sleeve by rods f³, f⁴. Air will now flow from conduit x through pipe v into cylinder u depressing a piston t which is connected to a foot valve r by rod s. The foot valve controls a port connecting conduits L, L', which supply air from the reservoir G to the loading station D.

When the load in cylinder a has been raised the sleeve f is then loosened and the loading station D turned from left to right until the cylinder a' takes the place of the cylinder a which latter will be inclined symmetrically to the position previously occupied by the cylinder a'. The sleeve f is now locked and the new load is ready to be raised while the cylinder a is ready to receive a piston and its load.

In order to prevent the sleeve f from being loosened during the ascent of the load there is provided a locking device M, Fig. 1^a, which locks the sleeve f when the tube is filled with air under pressure. Said locking device consists of a pipe j, communicating with tube B, a small cylinder p, a piston n and a piston rod and spring q.

In Fig. 1 are shown two unloading stations

E and E' occupying two floors but the description of the system and its mode of operation refers to a single receiving station.

An orifice *b* is formed in the wall of the tube B somewhat below the point of delivery of the load. As soon as the load in rising passes this orifice the air escapes to the exterior and the ascent ceases. The section of the said orifice *b* is regulated according to the inertia of the load so as to obtain a ready stoppage. If the elevator tube comprises several unloading stations only, the orifice *b* corresponding to the station where the load is stopped is opened. As soon as the ascent ceases, the load is caught by a stop, which consists of a bell-crank lever pivoted on the outside of the tube with one arm *m* normally projecting through a slot in the tube into the path of the piston. As the piston passes this point said arm is engaged and rocked on its pivot out of the path of the piston. As soon as the piston passes the arm will drop by gravity into its normal position and be held there against depression by the piston by means of the other arm *m'* of the lever engaging the tube.

For the removal of the load there is arranged in the wall of the tube B an opening, normally closed by a door *l* mounted on a hinge *k* having a lug *o* formed thereon. When the door is swung down into the position shown in dotted lines said lug engages the stem of a valve K mounted in the controlling conduit *x* and closes the latter.

When the door is closed and the load raiser is ready to operate anew the valve *r* is opened by the pressure in the controlling conduit *x*, as above described.

According to the loads to be raised the unloading station E may be replaced by a receptacle of any form whatever, such as a funnel or spout for example, in which the load is inclosed when it has abutted on the stop.

The two ends of cylinder *u* communicate by means of pipes *v*, *w* and conduit *x* with the air reservoir G; on one branch *w* is a cock *y* serving to regulate the quantity of air passed into said branch *w*.

The compressed air from the conduit *x* and pipe *v* enters the top of the cylinder *u* and by its pressure on the piston *t* overcomes the tension of the spring and opens the foot valve *r*. Consequently the air enters the cylinder *a* of the loading station and raises the load. But through the cock *y* the air enters slowly upon the other side of the piston *t* through the branch pipe *w* until its pressure together with the tension of the spring returns the piston *t* into its original position and closes the foot valve *r*.

The time employed in closing the valve and in consequence the quantity of air reaching the loading station is regulated by means of the cock *y* in proportion to the load and the height to which it is to be raised.

The valve Z in pipe *z* which communicates with the lower end of cylinder *u* opens at the same time that the sleeve *f* is loosened and allows the air in the cylinder below the piston to escape.

If one of the devices K, I, Z is damaged the work may be done by hand by means of valve N and a hand-pump.

The reservoir G may operate one or several elevator tubes.

The compressor H driven by an electric or steam motor (not shown) works continuously while the elevator is operating. It is provided with a manometer and a safety valve not shown.

When the elevator is employed for lowering the loads the tube or tubes works without a compressor or reservoir or automatic air delivery valve since the load in descending compresses the air under the piston C. This air slowly escapes to the exterior in passing through the valve N.

In the modified arrangement of the loading station shown in Fig. 2, four cylinders are employed the object being to increase the rapidity of the service or to work two elevator tubes with one loading station.

In the revolving arrangement of the loading station shown in said Fig. 2, the cylinders *a*, *a'*, are arranged concentrically in parallel around the pivot *b'* which pivot is also pierced by a longitudinal orifice *d* and a radial orifice *e*.

The last mentioned orifice *e* is arranged so as to correspond with the channel *c* of that one of the cylinders *a* which is in the prolongation of the elevator tube B.

A sleeve *j'* similar to the sleeve *f* in Fig. 1, serves to render air tight the junction of the tube and that one of the cylinders *a* which is in said prolongation.

I claim:

1. In an apparatus for raising and lowering loads, the combination with an elevator conduit and a compressed air conduit, of a plurality of loading cylinders adapted to successively register with the elevator conduit each provided with an air passage to connect the elevator and air conduit, means to vent the elevator conduit at a predetermined point to neutralize the pressure therein, and means in the conduit to engage a load raised above the venting means.

2. In an apparatus for raising and lowering loads, the combination with an elevator conduit and a compressed air conduit, of a plurality of pivoted loading members adapted to successively register with the elevator conduit and provided with air passages to connect the elevator and air conduits, a piston in the registering loading member of substantially the same diameter as the elevator conduit, means at elevator stations in the elevator conduit to automatically neutralize the pressure therein, and means at said sta-

tions to automatically engage a load raised thereto.

3. In an apparatus for raising and lowering loads, the combination with an elevator 5 conduit and a compressed air-conduit, of a plurality of loading cylinders pivoted below the elevator conduit and adapted to successively register with the lower end of the latter, each cylinder provided with a central air- 10 passage to connect the conduits, a door in the elevator conduit, means to vent the tube below the door, and means on the door to support a load carried thereto by the pressure in the conduit.
- 15 4. In an apparatus for raising and lowering loads, the combination with an elevator conduit and a compressed air-conduit, of a plurality of loading cylinders having air passages adapted to connect the conduits, a door 20 in the elevator conduit, means to vent the latter below the door, a controlling conduit and a valve in the latter automatically operated by the door when the latter is opened.
5. In an apparatus for raising and lowering loads, the combination with an elevator conduit and a compressed air conduit, of a 25 plurality of loading cylinders adapted to successively register with the elevator conduit
- and provided with a central air passage to connect the conduits, a coupling to connect 30 the elevator conduit and loading cylinders, a controlling conduit and a valve in the latter operated by the movement of the coupling.
6. In an apparatus for raising and lowering loads, the combination with an elevator 35 conduit having a discharge opening and a compressed air conduit, of a plurality of loading cylinders pivoted beneath the elevator conduit adapted to successively register with the latter and provided with a central air 40 passage to connect the conduits, a coupling to tightly connect the elevator conduit and loading cylinder, a controlling conduit, a valve in the latter operated by the coupling, means to vent the elevator below the opening, a door normally closing the latter, means on the door to support a piston, and a valve in the controlling conduit operated by the door.

In testimony whereof, I have signed my 50 name to this specification in the presence of two subscribing witnesses.
